CLAIM

The ornamental design for an emergency vehicle warning signal for automobiles, as shown and described.

DESCRIPTION

FIG. 1 is a perspective view of the emergency vehicle warning signal for automobiles embodying the design, with the wires broken away at the ends to indicate indeterminate length, of the present invention;

FIG. 2 is a side elevational view thereof;

FIG. 3 is a side elevational view thereof;

FIG. 4 is a rear elevational view thereof;

FIG. 5 is a front elevational view thereof;

FIG. 6 is a top plan view thereof; and,

FIG. 7 is a bottom view thereof.

FIG. 1

FIG. 2

FIG. 3

FIG. 4

FIG. 5

FIG. 6

FIG. 7
